UNITED STATES PATENT OFFICE.

GEORGE F. RITTER AND HARRY C. TILLOTSON, OF TOLEDO, OHIO, ASSIGNORS TO THE TILLOTSON MANUFACTURING COMPANY, OF TOLEDO, OHIO, A CORPORATION OF OHIO.

CARBURETOR.

Application filed December 23, 1914. Serial No. 878,693.

To all whom it may concern:

Be it known that we, GEORGE F. RITTER and HARRY C. TILLOTSON, citizens of the United States, residing at Toledo, Lucas County, Ohio, have invented new and useful Carburetors, of which the following is a specification.

This invention relates to carburetors.

This invention has utility when incorporated for mixing air with a fluid, especially for supply to internal combustion motors, as in motor vehicle work, there being special provision for automatic increase of supply with increase in the demand.

15 Referring to the drawings:

Fig. 1 is a medial vertical section through an embodiment of the invention in a carburetor for gasoline engine propelled motor vehicles;

20 Fig. 2 is a fragmentary section on the line II—II Fig. 1;

Fig. 3 is a perspective detail of the auxiliary inlet valve; and

25 Fig. 4 is a perspective view looking down upon the carburetor.

The carburetor comprises the main housing member or mixing chamber 1 having the annular seat 2 therebelow in engagement with which the chamber 3 carrying the float 4 may be locked in a plurality of angular positions as to the chamber 1. The float chamber 3 is held in position by the stem having the primary air supply passage 5 which has the threaded portion 6 engaging 30 with the threaded portion 7 of the main housing or mixing chamber 1.

35 The gasket 8 provides a liquid tight joint for the bottom of the float chamber 3. Centrally disposed in the upwardly extending portion 9 of the supply passage 5 is the needle valve 10 controlling the supply of liquid to the upwardly extending duct 11 having the radiating ports 12 delivering transversely of the portion 9 of the primary 40 air supply passage. The liquid from the float chamber 3 is supplied by the duct 13 to the valve 10. The valve 10 may be adjusted by the stem 14 therebelow. The gasket 15 is held in position by the gland 16 45 to make a liquid tight joint for the needle valve adjustment.

The portion 9 of the primary air supply

passage has a restricted or throat portion 17 adjacent the laterally extending radiating ports 12 which is provided by an extra internally mounted sleeve member having the venturi section 18. This sleeve is locked in position by the set screw 19.

55 While the primary air may to advantage be supplied through the passage 5 unwarmed and thereby avoid, especially in the summer season, drawing off too large a proportion of fuel from the ports 12, this normally rich mixture may be regularly made lean by a supply of warm air. This may be done by 60 jacketing the exhaust from the internal combustion motor and leading air heated by the exhaust through the duct 20 and passage 21 to pass around the outside of the first venturi section 18 and mix with the enriched 65 primary air in the second venturi section 22 in delivery to the mixing chamber 1. This section 22 is provided with an enlarged intake portion 23 directing the warmed air from the passage 21 for nicely commingling 70 with the unheated primary air. This second venturi may have a close fit in the housing 75 1. The throttle valve 24 may be manipulated by the crank 25.

80 In starting, to insure a rich mixture, the warmed air in the duct 20 may be cut off by the valve 26 as actuated by the crank 27.

85 In normal operation at varying speeds the supply of fuel to an internal combustion motor varies over a very wide range and the problem is to furnish an economical mixture to meet these conditions. Accordingly, in the device of this disclosure, besides the transverse fuel delivery in the primary passage for effective mixing, there is supplied 90 the warmed air for assisting in vaporization under normal operation; while with increased volume demand from the motor, automatic response may be had thereto through the reed or spring leaf valve 27' having 95 its free end adjacent the taper section 28 of the mounting member 29. This leaf 27' is held by the screw 30 in the head 31 of the member 29 mounted in position as to the housing 1 by the screws 32. This automatic leaf or reed valve 27' normally closes the opening 33 from the warmed air supply passage 20. As the engine speeds up or the demand on the carburetor is for increased 100

volume to such an extent as to reduce the pressure in the mixing chamber 1 beyond a determined degree for which the carburetor may be designed or set, the valve 27' will 5 open and supply warmed air to supplement the primary supply as assisted by the supply from passage 21. Should this supplementary or tertiary supply of warm air be a demand of some volume the flow thereof 10 through the passage 33 and over the ledge 28 will draw up fuel through the duct 34 from the float chamber 3 and thus automatically enrich this auxiliary air supply and thereby provide the motor with a proper 15 combustion mixture for effective operation.

In some instances of operation where in the speeding up of the motor there is not the power demand thereon or in some warm 20 season operations, this enriching of the supplementary or auxiliary air supply may not be necessary to insure a mixture and for eliminating such supply, there is provided a valve member 35 for closing the passage 34. This valve member 35 has the disk 36 25 on its face provided with cross grooves 37 and may be rotated by the handle 38 to bring either of said grooves in line with the spring holding pointer 39 which will hold the valve in the closed or open position as desired.

30 The clamp ears 40 are in position to carry a guide for manipulating the crank 27 and controlling the warm air supply. The warmed air supply passage 20 is to advantage deflected as shown to permit convenient mounting as to the exhaust passages and fuel supply connections of a motor. The various angular positions in which the float chamber 3 may be placed allow most advantageous positioning of the supply chamber 35 35 in caring for the fuel supply line thereto.

40 Any condensation in the mixing chamber 1 may drain off through the passages 42 and have re-entrance for vaporization by the warm auxiliary air from the passage 45 41 supplied to the venturi 22.

In operation, the carburetor may have its liquid fuel supply thereto through the float controlled valve in the chamber 41. With the supply of liquid fuel in the float chamber 50 3, the starting of the motor will cause an inrush of primary normal atmospheric air through the passage 5, which in entering the throat 17 at the increased velocity will draw out of the laterally extending 55 ports 12 the liquid fuel, which in its flow being directed transversely of the inrushing primary air thoroughly permeates said air volume and as entrained thereby rises in the venturi 18 expanding in such travel 60 to approach vaporization, which is assisted by the warming action of the air in the passage 21. This rich mixture is thus subject to the inrushing warm or secondary air from the passage 21 and is directed by the 65 portion 23 of the venturi 22 to effectively

bring about thorough vaporization in the venturi 22 delivering to the mixing chamber 1 directly below the throttle 24.

In starting, it may be desirable to have instead of this normal mixture a rich mixture which may be accomplished by shutting off the secondary air by means of the valve 26. The increased volume demand upon the carburetor beyond the capacity of the primary passage 5 gradually reduces 75 the pressure in the mixing chamber 1, and the valve 27' is thereby unbalanced admitting a tertiary air supply to supplement the mixture in the combustion chamber 1. With just a slight volume of this supplementary 80 warmed air supply, there will not be suction sufficient to draw any enriching fuel through the passage 34 but with increased volume there is the automatic pulling of enriching fuel to commingling with the warmed air by spraying or jetting against the reed or leaf valve and being drawn through into the mixing chamber by this inrushing volume.

85 There is accordingly provided in this carburetor a device which will economically operate under a wide range of conditions and thereby cooperate with a motor for maximum power with a minimum of fuel.

90 This economy of operation extends to economy in starting as well as facility in starting. Throttling of the air to enrich the mixture occurs by closing the valve 26. However, this closing of the valve 26 does not cut off the air but leaves the primary air supply passage 5 open to supply through the venturi 18 a rich fuel mixture to the mixing chamber 1 as supplied by the fuel delivery ports 12. This rich mixture from the venturi 18 is the rich mixture passing 95 the throttle valve 24 when the valve 26 is closed as the second venturi 22 does not operate to dilute or reduce the richness of this mixture. Under these circumstances, the choking of the air at the only place that the air is to be choked at the valve 26, does not completely cut off the air supply because there is the air supply through the passage 5, and so it is not possible to flood 100 the motor with fuel and no air to assist in combustion.

105 110 What is claimed and it is desired to secure by Letters' Patent is:

115 120 1. A carburetor comprising the combination of a mixing chamber, a primary fuel and air supply passage communicating with said mixing chamber and continuously open for the passage of air therethrough, an auxiliary air supply passage communicating with said mixing chamber, an automatically operable air intake valve controlling the communication between said auxiliary passage and said mixing chamber, a choke valve in said auxiliary passage, and a passage connecting said auxiliary pas- 125 130

- sage with said primary passage and opening into said auxiliary passage between said air intake valve and said choke valve.
2. A carburetor comprising the combination of a mixing chamber, a primary fuel and air supply passage communicating with said mixing chamber, an auxiliary air supply passage communicating with said mixing chamber, an auxiliary fuel nozzle located in said auxiliary air supply passage, a flexible reed rigidly secured at one end and having its free end extending toward said primary supply passage, said flexible reed controlling communication between said auxiliary passage and said mixing chamber, and a passage connecting said auxiliary passage with said primary supply passage for conducting air to the said primary supply passage independently of the operation of the reed valve.
3. A carburetor comprising the combination of a mixing chamber, a primary fuel and air supply passage communicating with said mixing chamber, an auxiliary air supply passage separate from said primary supply and communicating with said mixing chamber, a flexible valve mounted to control the communication between said mixing chamber and said auxiliary passage and having its free end extending towards said primary supply passage, and a passage connecting said auxiliary passage and said primary passage in advance of said mixing chamber.
4. A carburetor, embodying a continuously open primary fuel and air supply passage, a chamber with which said passage communicates, an auxiliary air supply passage having therein a valve, a duct leading from said auxiliary passage in advance of the valve, said duct being in communication with the primary passage in advance of its point of communication with the chamber, and means for closing said auxiliary supply passage in advance of said duct.
5. A carburetor, embodying a primary air supply passage, means for supplying fuel to said passage, a supplemental air supply passage, means for supplying fuel to said supplemental air supply passage, and a secondary air supply passage for reducing richness of the mixture of the primary supply passage, said secondary passage leading from the supplemental air supply passage.
6. A carburetor embodying a primary air supply passage, means for supplying fuel to said passage, a supplemental air supply passage, means for supplying fuel to said supplemental air supply passage, a secondary air supply passage communicating directly with said primary air supply passage for reducing the richness of the mixture of the primary air supply passage,
- and common means for controlling the volume of air to be admitted to the supplemental air supply passage and to the secondary air supply passage.
7. In a carburetor, a primary air and fuel supply passage, a secondary air supply passage, separate and independent from said primary air supply passage, a supplemental air supply passage, the secondary air supply passage being connected with the supplemental supply passage and the primary fuel supply passage, and common means for controlling the admission of air to said secondary air supply passage and to said supplemental air supply passage.
8. In a carburetor, a primary air supply passage of venturi form, a fuel supply means therefor, a second venturi provided with a throat into which said first mentioned venturi delivers, a secondary air supply for said second venturi, separate and independent from said primary air supply passage, a valve for controlling said secondary air supply passage, and a supplemental air and fuel supply passage opening above the second venturi for admitting fuel when suction is increased in the carburetor.
9. In a carburetor, a primary air supply passage of venturi form, a fuel supply therefor, said air supply passage being continuously open, a second venturi into which said first mentioned venturi delivers, a mixing chamber located above said second venturi, the second venturi being provided with openings for conducting the condensed portion of the fuel from the mixing chamber to the primary air passage, a secondary air supply for said second venturi separate from said primary air passage, a valve for controlling said secondary air supply passage, and a supplemental air and fuel supply passage.
10. In a carburetor, a primary air supply passage of venturi form, a fuel supply means therefor, a second venturi into which said first mentioned venturi delivers, a secondary air supply passage to said second venturi, separate from said primary air supply passage, a supplemental air supply passage, and common means for controlling the supply of air to the secondary supply passage and the supplemental supply passage.
11. In a carburetor, a mixing chamber, a primary air and fuel supply passage, a venturi communicating with the same, a supplemental air and fuel supply passage, and a secondary air supply passage leading from the supplemental air supply passage and discharging through said venturi into the path of the vaporized fuel in the primary supply passage before its admission into the mixing chamber.
12. In a carburetor, a primary air and

fuel supply passage, a supplemental air and supply passage, and a secondary air supply passage having a common inlet with the supplemental air supply passage and opening into the path of the vaporized fuel from the primary supply passage before it joins the supplemental supply passage.

In testimony whereof we affix our signatures in the presence of two witnesses.
